LANDING GEAR FOOT

Hyle K. Clafin, Kent, Mich., assignor to
Westran Corporation

Filed Jan. 28, 1974, Ser. No. 437,508

Term of patent 14 years

Int. Cl. D12—16

U.S. Cl. D12—217

Fig -1

Fig -2

Fig -3

Fig -4

Fig -5

FIG. 1 is a perspective view of the landing gear foot of my present design;

FIG. 2 is a top view of the landing gear foot of FIG. 1;

FIG. 3 is a bottom view of the landing gear foot of FIG. 1;

FIG. 4 is a side elevational view of the landing gear foot of FIG. 1; and

FIG. 5 is an end elevational view of the landing gear foot of FIG. 1.

I claim:

The ornamental design for a landing gear foot, as shown.
